Branch Harris Colby.

UNITED STATES PATENT OFFICE.

BRANCH HARRIS COLBY, OF HILSDALE, MICHIGAN.

PRESCRIPTION-FILE FOR PRESERVING PRESCRIPTIONS.

SPECIFICATION forming part of Letters Patent No. 327,140, dated September 29, 1885.

Application filed April 20, 1885. (No model.)

To all whom it may concern:

Be it known that I, BRANCH HARRIS COLBY, a citizen of the United States, residing at Hillsdale, in the county of Hillsdale and the 5 State of Michigan, have invented a new and useful Prescription-File for Preserving Prescriptions in a way so safe and compact that any desired prescription can be quickly found, removed from, and replaced in the file whenever necessary.

My invention consists of a new style of book, the leaves of which are removable and made of cloth or cloth and paper combined, so arranged and constructed that each page contains one hundred receptacles or pockets, each 15 pocket being intended to hold one prescription. Each page has printed upon it certain numbers and figures arranged in a specified way, so that the number of every pocket is clearly and accurately indicated and quickly found.

The objects of my invention are, first, to provide a secure and compact book to hold prescriptions; secondly, to furnish a separate 25 receptacle for each prescription, and, thirdly, to provide a system of numeration by which any desired prescription can be instantly found.

My invention is designed for the use of 30 druggists.

The common practice among druggists is to number their prescriptions and paste them into a blank-book made for the purpose or hang them upon a wire hook. By the first 35 way much time is lost in pasting, and the second way does not admit of ready reference to prescriptions which it is desired to consult subsequently, and prescriptions once filed by either method cannot be removed for consultation or a second filling.

By my method the prescriptions are first numbered, as heretofore, then folded and inserted in a correspondingly-numbered pocket in the file, where they can be instantly found, removed, and replaced whenever desired.

The construction of my prescription-file will be sufficiently understood by reference to the accompanying drawing, one figure being sufficient to illustrate my invention.

50 The figure represents one side of a double leaf of the file before the leaves are bound.

The other side of the leaf is like the one shown.

The leaves are made double, this being more a mechanical convenience of construction than 55 an essential feature of the invention—that is, one piece of cloth is so folded as to form two leaves. Each double leaf will hold four hundred prescriptions, two hundred to each leaf and one hundred upon each page.

6c A double leaf is made as follows: A piece of cotton cloth of suitable size is folded twice, (see drawing,) the ends meeting in the middle of the double leaf at M M. A single piece of cloth or strong paper of the same size as the 65 folded double leaf is then placed between the two folds of cloth. Rectangular pockets for holding prescriptions are then formed by sewing the cross seams E E and the vertical seams V V and cutting openings in the cloth at the 70 top of each rectangle formed by the intersecting seams. The portion of the leaf included between H A and F L is left for binding. The double leaf being now folded so that L A will fall upon F H, and a final seam being made 75 through the superimposed leaves at L A F H, thus form an inclosed space into which is thrust a stub of suitable dimensions to make the leaves of uniform thickness when bound and filled with prescriptions.

80 The figure shows the page at the left with all the pockets empty and the page at the right with a prescription in each pocket. Each page contains one hundred pockets. At the upper left-hand corner of each page is 85 printed the full number of the first pocket upon that page, and this number stands as an initial number of hundreds for each of the pockets upon that page. Thus, if the number upon the upper left-hand pocket of a page is 90 1800, then all the pockets upon that page will be numbered eighteen hundred and something, the precise number of any pocket being determined by the numbers 10, 20, 30, &c., at the left-hand side of the page, representing 95 tens to be added to the initial hundred of the page, (in this case 1800,) and by the numbers 1, 2, 3, &c., at the top of the page, representing units to be added to the hundreds and tens. Thus the pockets marked N, T, and U 100 would be numbers 1800, 1856, and 1899, respectively.

Suppose it is desired to file prescription number 1856. The druggist, having first numbered the prescription, will then turn to the page of the file having 1800 printed upon its upper left-hand corner, then run his eye down the column of figures upon the left-hand side of the page until he comes to the number 50. His eye will then follow that row of pockets to the right until it comes to the vertical row 10 of pockets marked 6 at the top of the page. He has now arrived at the desired pocket, viz: No. 1856, and tucks the folded prescription into the pocket, where it will remain until needed, and can then be found, as described, 15 taken out for consultation or refilling, and then replaced.

I intend to bind the leaves of my file with the "Emerson file-binder" or with some one of the numerous file-binders made for binding 20 periodicals or folios, the use of which admits of increasing or diminishing the number of

leaves, which is a great convenience; or the leaves may be bound into a volume in the usual way.

What I claim as my invention, and desire 25 to secure by Letters Patent, is—

A prescription-file made in book form, the leaves of which are made of cloth or cloth and paper, with exactly one hundred pockets upon each page, the pockets being arranged in 30 ten horizontal and ten vertical rows, with numbers at the top and left-hand side of each page, the numbers forming an index to each pocket, the precise number of each pocket being determined by its relative position in reference 35 to the aforesaid numbers, all as herein described.

BRANCH HARRIS COLBY.
